UNITED STATES PATENT OFFICE.

JULIUS J. MILLER, OF ST. JOSEPH, MICHIGAN, ASSIGNOR, BY MESNE ASSIGNMENTS, TO WIREBOUNDS PATENTS COMPANY, OF KITTERY, MAINE, A CORPORATION OF MAINE.

WIRE-BOUND-BOX MACHINE.

1,260,986.

Specification of Letters Patent. Patented Mar. 26, 1918.

Application filed March 7, 1912. Serial No. 682,097.

To all whom it may concern:

Be it known that I, JULIUS J. MILLER, a citizen of the United States of America, and resident of St. Joseph, Berrien county, Michigan, have invented a certain new and useful Improvement in Wire - Bound - Box Machines, of which the following is a specification.

My invention relates to machinery for the manufacture of wire bound boxes of that kind in which the sides of the box are provided with reinforcing cleats which are secured to the heads or end walls of the box, and in which binding wires are provided which extend like hoops around the exterior of the box, the said cleats and binding wires coöperating to render the box strong and serviceable in use.

Prior to my invention, the general custom has been, in the manufacture of these boxes by machinery, to secure the cleats to the veneer at the same time that the binding wires are stapled thereto, in one machine, and to then employ another machine for stapling the heads or end walls to the said cleats. It has also been proposed to simply apply the binding wires to the strips of veneer, in one machine, to form a flexible blank without cleats, and to then secure this blank, by hand, to the edges of the end walls or heads of the box, in any suitable manner, as by simply nailing the ends of the strips of veneer of the blank to the cleats already secured to the end walls or heads of the box.

My invention contemplates, however, the manufacture of these boxes by machinery which will staple the sides of the box to the cleats of the end walls thereof after the said cleats have been secured to the said heads or end walls. In other words, my invention contemplates a machine which will automatically staple a cleatless flexible wire bound blank to the cleats of the end walls or box heads which have been previously prepared or made in any suitable manner. In this way, and by this method, I not only obviate the necessity of providing mechanism for spacing the cleats apart endwise in the machine for making the wire bound blanks, but also the necessity of resorting to hand methods, such as ordinary nailing, for securing the blanks to the heads or end walls. Furthermore, my invention contemplates a machine for this purpose which will operate on boxes of different sizes, without any

changes or adjustments therein, whereby it is not necessary to lose time in changing and adjusting the machine when the size of the box is to be changed or varied. In other words, the transverse dimensions of the box can be changed or varied at will, but not the length or longitudinal dimension thereof, without the necessity of making any changes or adjustments in the machine.

My invention, furthermore, contemplates a machine, of this general character, which will not only secure the veneer to the cleats which have been previously secured to the heads or end walls, but which will also, and by one and the same operation, secure the binding wires to the exterior of the box. In other words, my invention contemplates, broadly, a machine which will, by one and the same operation, apply the binding wires and secure the heads or end walls in place at the ends of the box. By this method no preliminary stapling of the wires to the veneer is necessary, as by reason of my improvement the staples which secure the wires in place serve also to fasten the veneer to the cleats, notwithstanding that these cleats have been previously secured to the heads or end walls of the box.

The nature and advantages of my invention will, however, hereinafter more fully appear.

In the accompanying drawings:—

Figure 1 is a front elevation of a machine embodying the principles of my invention.

Fig. 2 is a perspective of one of the panel-like heads or end walls of the box.

Fig. 3 is a vertical section on line 3—3 of Fig. 1.

Fig. 4 is a perspective of one of the wire bound blanks involved in the method of manufacture contemplated by the machine shown in Figs. 1 and 3.

Fig. 5 is an enlarged detail view of one of the feed roll devices for producing a step by step motion of the box while it is being stapled.

Fig. 6 is a perspective of one of the sliding stops, there being one of these for each set of feed rolls.

Fig. 7 is a front elevation of the mechanism shown in Fig. 5.

Fig. 8 is a vertical section on line 8—8 in Fig. 7.

Fig. 9 is a view similar to Fig. 3, but showing a machine provided with means for

applying binding wires at the same time that the sheets of veneer are stapled to the cleats of the end walls.

Fig. 10 is a detail front elevation of the feed mechanism at the left hand side of the machine.

As thus illustrated, my invention comprises a frame A mounted on a base a_1 , and provided at a point above with the usual 10 stationary cross-bar a^1 , for the stapling heads B and C, which latter are operated in the usual manner by the vertically reciprocating cross bar a^2 disposed at a point above and mounted to slide up and down in slots 15 in the said frame. The usual driving shaft D is provided near the bottom of the machine, and arranged to extend transversely thereof, said shaft being connected by eccentrically operated pitmen d , with the ends 20 of the cross-bar a^2 , whereby the said shaft is operative to actuate the usual staple formers and drivers of the said stapler heads. Each stapler head is provided with a staple wire feeding device E, which is operated by 25 the pawl e , carried on the cross-bar a^2 , the staple wire being thus taken from the reels e^1 at the top of the machine and fed through the usual guide tubes e^2 behind the staplers.

The construction and devices so far described are ordinary and common, and do not require further explanation.

The feed mechanism for feeding the box along while it is being stapled is as follows:—

35 The castings or uprights F and F^1 are mounted on the base of the machine and disposed adjacent the staplers B and C, respectively, each casting or upright being preferably immediately outside of its allotted 40 stapler. As the feeding mechanism and other equipment is the same on one casting or upright as it is on the other, a description of one will be sufficient. The mechanism on the casting or upright F comprises 45 a shaft f , extending horizontally and transversely of the machine, mounted in the upper end of said casting or upright, and a sharp-toothed feed wheel f^1 fixed on the inner end of said shaft at a point directly below the line of downward thrust of the adjacent stapler. At its outer end, the said shaft f is provided with a sprocket wheel f^2 , which is connected by a sprocket chain f^3 with a sprocket wheel f^4 on the shaft f^5 , 50 which extends entirely across the machine, and which is mounted at its ends in suitable bearings on the main frame of the machine. The top of the casting or upright F is provided with vertical guides f^6 , in which the 55 bearing blocks f^7 are mounted to slide up and down, each block being provided with a laterally projecting stud f^8 upon which is mounted a roll f^9 , the axes of these rolls being disposed in the same horizontal plane 60 and extending transversely of the machine.

A plate f^{10} is secured to the upper ends of said guides, and springs f^{11} are interposed between the bottom of these plates and the tops of said vertically movable blocks, whereby the rolls f^9 are yieldingly held 70 against upward movement. Screws f^{12} are provided in the plate f^{10} for adjusting the tension of said springs. It will be seen that the toothed feed roll f^1 is disposed centrally of the distance between the two rolls f^9 , 75 whereby the stapler B is adapted to operate between these rolls and drive the staples downwardly between the upper rolls f^9 , the lower roll sustaining the downward thrust incident to the driving of the staples. A 80 movable back stop or gage f^{13} is disposed at a point back of the feed rolls, and is mounted upon a U shaped frame f^{14} , which slides on the casing F, being guided, for example, by the ribs f^{15} which run in slots formed in 85 the top of the casting F, as shown more clearly in Fig. 8. This frame is also provided with beveled portions f^{16} which engage the rolls or projections f^{17} on the blocks f^7 (which rolls or projections f^{17} 90 move up and down along the beveled portions of the guides f^{16}) whereby the movement of the back stop or gage f^{13} into the path of the box serves also to raise the rolls to facilitate the insertion of the cleats and 95 veneer between the upper and lower feed rolls. The frame f^{14} is held normally retracted by the springs f^{18} , whereby the back stop or gage f^{13} is normally out of the path of the box. The frame f^{14} is provided with 100 a roll or projection f^{20} , and the side of the casting or upright F is provided with a vertically reciprocating bar f^{21} having its upper end provided with a bevel f^{22} that engages the roll or projection f^{20} , whereby the 105 upward movement of this bar causes the frame f^{14} to move forward. This bar f^{21} is actuated by a foot treadle f^{23} near the bottom of the machine, or by any other arrangement. The shaft f^5 is actuated by a 110 ratchet feed mechanism f^{24} of any suitable known or approved character, which mechanism is in turn operated by a pitman f^{25} which is connected at its lower end with a cam mechanism f^{26} on the shaft D at the 115 bottom of the machine.

By this arrangement the feed rolls f^1 are actuated intermittently to cause a step by step forward feeding motion of the box.

The method of using the machine thus 120 constructed is as follows:

The operator places two of the end walls or panels shown in Fig. 2 in the machine, with the cleats outside, and with the first cleat of each panel or end wall disposed in 125 position between the upper and lower feed rolls, whereby the lower edge of each cleat is prehensilely engaged by the teeth of the feed rolls in the manner shown in Figs. 1 and 3.

At the time that this is done the operator also presses the foot treadle f^{23} , thereby causing the back stops or gages f^{13} to move toward each other and into the path of the 5 cleats, and at the same time causing the upper rolls f^9 to move upward, thereby making it comparatively easy to insert the said end walls into place. This also permits the operator to place the end of the blank shown 10 in Fig. 4 below the rolls f^9 , and in place against the upper ends of the back stops or gages f^{13} , whereby the forward edge of the blank overhangs the ends of the cleats. This blank, of course, as shown in Fig. 4, is previously 15 made by wiring together a plurality of sheets or strips of veneer or other suitable material. When the heads or end walls and the flexible blank are thus adjusted into position, the operator then releases the foot treadle f^{23} , thereby causing the back stops or gages f^{13} to withdraw laterally from the path of the cleats, and causing the upper rolls f^9 to move downward and bear upon the upper surface of the veneer. Then the 20 machine is controlled by the usual clutch mechanism (not shown) provided in stapling machines of this character, and the step by step feeding motion communicated through the transmitting connections to the 25 sprocket wheels f^2 , causes the box to move forward in a step by step manner, and at the same time the reciprocation of the staplers in the usual and well known manner effects the insertion of staples through the 30 veneer and into the cleats, these staples being inserted in any suitable manner relative to the binding wires. As shown, the staples are inserted along lines immediately 35 outside of the said binding wires, whereby the binding wires travel along inside of the feed rolls in the manner shown more clearly in Fig. 1. When the first cleats are thus stapled to the veneer of the blank, and as soon 40 as the corner of the box approaches the rolls, the box turns over—that is to say, makes a quarter turn, it being taken into account that this is possible by reason of the fact that the 45 rolls f^9 are capable of rising to permit this rotary motion of the box. In other words, the toothed feed rolls f^2 travel along the inner edges of the cleats, and when the box turns over the operator may assist in this 50 operation or manipulation of the work, if such is necessary. When the ends of the 55 last cleats pass out from behind the rolls, the box then falls to the floor, or is otherwise taken care of, it being observed that the panels or end walls have only three cleats, the gap formed by the omission of the fourth 60 cleat being necessary to the convenient manipulation of the box in the machine.

Referring to Figs. 9 and 10, it will be seen that the machine in this case is exactly the same as the one previously shown and described, except that it is provided with

means for supplying binding wires G below the upper rolls f^9 , the latter being preferably grooved for this purpose, but which grooving is not necessary in Figs. 1 to 8, as the rolls travel at one side of the previously applied binding wire, whereby the said binding wires are applied at the same time that the veneer is stapled to the cleats. In other words, the cleats and binding wires are stapled to opposite sides of the veneer by one 75 and the same operation, notwithstanding that the said cleats have been previously secured to the heads or end walls of the box. In this way, no preliminary wiring of the sheets of veneer constituting the sides of 80 the box is necessary, as the only preliminary work is the stapling or nailing of the cleats to the thin boards of the end walls, and thus the entire amount of work is reduced to merely two operations for each box. 85

With the construction previously described, such as that shown in Figs. 1 to 8, inclusive, three operations are necessary, to wit: the securing of the cleats to the end walls of the box, the wiring of the veneer 90 together, and then the stapling of the blank to the cleats of the end walls. Even this, I find is possessed of considerable advantage, and characterized by more or less economy over the old methods, in view of the fact 95 that the wiring of the veneer together without cleats is a very simple operation, and can be carried on at greater speed and with less necessity for interruption than when the cleats are fastened to the veneer at the same 100 time that the binding wires are secured thereto. However, as explained, and with the construction shown in Figs. 9 and 10, only two operations are necessary, to wit: the stapling or nailing of the cleats to the 105 heads or end walls of the box, and the stapling of the wire and the veneer to the said cleats. As either machine will operate on a box of any transverse dimension, without any changing or adjustment, it follows that 110 the work can be carried on in a fast and convenient manner, with less interruption than heretofore, which is of considerable importance when machinery of this kind is employed for the manufacture of boxes of different sizes, it being found desirable at 115 times to make only a few boxes of each size.

It will be understood, of course, that the machine shown and described is adjustable, in any suitable manner, for boxes of different lengths. In other words, the staplers are adjustable toward and away from each other, and the castings or uprights F and F^1 are also adjustable toward and away from each other, whereby the machine can be used 120 for operating on boxes of different lengths. It is only when the length of the box is changed that it is necessary to change or adjust the machine, but this can be done quickly and without undesirable delay. In 125 130

Figs. 9 and 10 the construction is such that the operator simply places the two heads or end walls in position and then inserts a sheet of veneer and then starts the machine. 5 First one side and then the other of the box then travels through the feed rolls, until the sides are all stapled to the cleats, and at the same time the binding wires are secured in place by the same staples that are employed 10 to fasten the veneer to the cleats. Thus the binding wires are stapled to the veneer and cleats after the cleats are secured to the heads or end walls of the box.

My invention as illustrated in Figs. 9 and 15 10 is also operative and useful in the following manner:

The end walls can be made, as previously described, and sheets or strips of veneer can then be preliminarily or partially secured 20 to the cleats of said end walls, either by hand or by means of the machine shown in Figs. 1, 2 and 8, inclusive. Afterward, and by means of the machine shown in Figs. 8 and 9, the binding wires can be applied to 25 the exterior of the box. In other words, by my invention I make it possible to apply binding wires to the exterior of a box or crate, after the said box or crate is completed except for the said wires.

30 In the previously described machines, which are illustrative of my invention, it will be seen that no portion of the machine extends inside of the box. The feed mechanism for feeding the box heads bodily forward operate entirely outside of the box, and as shown is adapted to engage the edges of the cleats of a paneled or counter-sunk head, and is equipped with guide rolls which bear downward upon the sheets or sides of 35 the box to hold the latter upon the cleats, as well as to maintain the cleats in operative engagement with the toothed rolls which produce the forward feeding motion. As explained, the guide rolls f^o are adapted 40 to rise as soon as the toothed rolls engage the vertically disposed cleats, and when this occurs the partially completed box rotates about a horizontal axis adjacent one corner thereof, which axis is coincident with the 45 common axis of the toothed feed rolls. This partial rotation of the box occurs at the two bottom corners of the box, whereby the box is partially rotated twice before the final stapling operation. Thus the feed 50 mechanism and the box not only change their relative positions while the box is being moved forward bodily, but in addition the box is turned over and its position relative to the feed mechanism is changed in 55 this respect also. With this mode of operation, it is, of course, possible to employ the machine shown in Fig. 3 for making a box without any binding wire, and to then afterward employ the machine shown in Fig. 9 60 65 for simply applying the binding wire to

the said previously constructed box. As shown in Fig. 9 means are provided for feeding the binding wire G to the first upper roll f^o , in the manner previously described, and as this roll is a part of the 70 mechanism for feeding the box heads forward it follows that this mechanism is operated to feed in unison the three superposed elements of the box, to-wit, first the wire, second the veneer or box side, and third 75 the cleat of the box head, the three pieces of material being clamped together and fed forward in a step by step manner. Thus, and with machines constructed in accordance with my invention, it is possible to 80 apply the binding wire at the same time that the heads of the box are fastened in place, or to apply the said binding wire to the sheet material or the sides of the box either before or after the heads are fastened in 85 position at the ends of the box.

What I claim as my invention is:

1. A machine for making boxes, comprising feed mechanism for successively engaging the cleats on the heads of the box, arranged to permit rotation of the box about a longitudinal axis, and means for stapling sides to the said cleats. 90

2. A machine for making boxes, comprising feed mechanism for engaging the cleats 95 on the heads of the box, arranged to permit rotation of the box about a longitudinal axis, and means for stapling sides to the said cleats, said mechanism comprising toothed rolls arranged to engage the lower 100 edges of the cleats to feed and support the box during the stapling operation.

3. A machine for making boxes, comprising feed mechanism for engaging the cleats 105 on the heads of the box, arranged to permit rotation of the box about a longitudinal axis, means for stapling sides to the said cleats, said mechanism comprising upper rolls which yieldingly bear upon the box, and lower rolls upon which the box is supported and is free to turn about said axis. 110

4. A machine for making boxes, comprising feed mechanism for engaging the cleats on the heads of the box, arranged to permit rotation of the box about a longitudinal 115 axis, and means for stapling sides to the said cleats, said mechanism comprising a single supporting roll at each side of the machine, said rolls being arranged to engage the lower edges of the cleats, each roll being 120 directly under a staple driver.

5. A machine for making boxes, comprising feed mechanism for successively engaging the cleats on the heads of the box, arranged to permit rotation of the box about a longitudinal axis during the fastening of the sides to the cleats, and means for stapling the sides to the said cleats, said mechanism comprising holding means arranged 125 to rise over the corners of the box. 130

6. A machine for making boxes, comprising feed mechanism for engaging the cleats on the heads of the box, arranged to permit rotation of the box heads about a common axis, and means for stapling sides to the said cleats, said mechanism comprising means for successively engaging the cleats on the heads of the box.
7. A machine for making boxes, comprising feed mechanism for successively engaging the cleats on the heads of the box, arranged to permit rotation of the box heads about a common axis, means for stapling sides to the said cleats, and movable back stops for correctly positioning the parts of the box.
8. A machine for making boxes, comprising feed mechanism for engaging the cleats on the heads of the box, arranged to permit rotation of the box about a longitudinal axis, means for stapling sides to the said cleats, said mechanism comprising toothed rolls arranged to engage the lower edges of the cleats to feed and support the box during the stapling operation, and movable back stops for correctly positioning the parts of the box.
9. A machine for making boxes, comprising feed mechanism for engaging the cleats on the heads of the box, arranged to permit rotation of the box about a longitudinal axis during the general operation of attaching the sides to the cleats, means for stapling sides to the said cleats, said mechanism comprising upper rolls which yieldingly bear upon the box, lower rolls upon which the box is supported free to turn about said axis, and movable back stops for correctly positioning the parts of the box.
10. A machine for making boxes, comprising feed mechanism for engaging the cleats on the heads of the box, arranged to permit rotation of the box, about a longitudinal axis, means for stapling sides to the said cleats, said mechanism comprising a single supporting roll at each side of the machine, said rolls being arranged to engage the lower edges of the cleats, each roll being directly under a staple driver, and movable back stops for correctly positioning the parts of the box.
11. A machine for making boxes, comprising feed mechanism for successively engaging the cleats on the heads of the box, arranged to permit rotation of the box about a longitudinal axis, means for stapling sides to the said cleats, said mechanism comprising holding means arranged to rise over the corners of the box, and movable back stops for correctly positioning the parts of the box.
12. A machine for making boxes, comprising feed mechanism for successively engaging the cleats on the heads of the box, arranged to permit rotation of the box about a longitudinal axis during the general operation of attaching the sides to the cleats, means for stapling sides to the said cleats, and means for feeding binding wires to the stapling means, whereby the said box heads are fastened in place at the same time that the binding wires are secured to the exterior of the box.
13. A machine for making wire bound boxes, comprising feed mechanism for successively engaging the cleats on the heads of the box about a longitudinal axis during the general operation of attaching the sides to the cleats, means for stapling sides to the said cleats, and means for feeding binding wires to the stapling means, whereby the said box heads are fastened in place at the same time that the binding wires are secured to the exterior of the box.
14. A machine for making wire bound boxes, comprising feed mechanism for engaging the cleats on the heads of the box, arranged to permit rotation of the box about a longitudinal axis, means for stapling sides to the said cleats, said mechanism comprising toothed rolls arranged to engage the lower edges of the cleats to feed and support the box during the stapling operation, and means for feeding binding wires to the stapling means, whereby the said box heads are fastened in place at the same time that the binding wires are secured to the exterior of the box.
15. A machine for making wire bound boxes, comprising feed mechanism for engaging the cleats on the heads of the box, arranged to permit rotation of the box about a longitudinal axis during the general operation of attaching the sides to the cleats, means for stapling sides to the said cleats, said mechanism comprising upper rolls which yieldingly bear upon the box, and lower rolls upon which the box is supported and free to turn about said axis, and means for feeding binding wires to the stapling means, whereby the said box heads are fastened in place at the same time that the binding wires are secured to the exterior of the box.
16. A machine for making wire bound boxes, comprising feed mechanism for engaging the cleats on the heads of the box, arranged to permit rotation of the box about a longitudinal axis, means for stapling sides to the said cleats, said mechanism comprising a single supporting roll at each side of the machine, said rolls adapted to engage the lower edges of the cleats, each roll being directly under the said stapling means, and means for feeding binding wires to the stapling means, whereby the said box heads are fastened in place at the same time that the binding wires are secured to the exterior of the box.
17. A machine for making wire bound boxes, comprising feed mechanism for engaging the cleats on the heads of the box, arranged to permit rotation of the box about a longitudinal axis during the general operation of attaching the sides to the cleats, means for stapling sides to the said cleats, and means for feeding binding wires to the stapling means, whereby the said box heads are fastened in place at the same time that the binding wires are secured to the exterior of the box.

boxes, comprising feed mechanism for successively engaging the cleats on the heads of the box, arranged to permit rotation of the box about a longitudinal axis, means for 5 stapling sides to the said cleats, said mechanism comprising holding means arranged to rise over the corners of the box, and means for feeding binding wires to the said stapling means, whereby the said box heads 10 are fastened in place at the same time that the binding wires are secured to the exterior of the box.

18. A machine for making wire bound boxes, comprising feed mechanism for 15 gaging the cleats on the heads of the box, arranged to permit rotation of the box about a longitudinal axis during the general operation of attaching the sides to the cleats, means for stapling sides to the said cleats, 20 said mechanism comprising means for successively engaging the cleats on the heads of the box, and means for feeding binding wires to the stapling means, whereby the said box heads are fastened in place at the 25 same time that the binding wires are secured to the exterior of the box.

19. A machine for making boxes, comprising feed mechanism for successively engaging the cleats on the heads of the box, 30 arranged to permit rotation of the box about a longitudinal axis, said mechanism arranged to cause said heads to move bodily forward in unison, means for stapling sides to the said cleats, said mechanism having 35 elements to guide the cleats endwise in a straight line, and devices for controlling said elements to permit successive rotations of the box at the corners thereof.

20. A machine for making boxes, comprising feed mechanism for successively engaging the cleats on the heads of the box, 40 arranged to permit rotation of the box about a longitudinal axis, means for stapling sides to the said cleats, means to actuate said mechanism a plurality of times for each side of the box, and instrumentalities to operate said 45 means a plurality of times for each side.

21. A machine for making boxes, comprising feed mechanism for successively engaging the cleats on the heads of the box, 50 arranged to permit rotation of the box about a longitudinal axis, and means for stapling sides to the said cleats, said mechanism having cleat-engaging rolls which rotate about 55 a fixed horizontal axis, there being space to permit insertion of the two heads in position between said rolls.

22. A machine for making boxes, comprising feed mechanism for successively engaging the cleats on the heads of the box, 60 arranged to permit rotation of the box about a longitudinal axis, means for stapling sides to the said cleats, elements for engaging the ends of the first cleats to position the heads 65 on said mechanism, and means to move said

elements into and out of the path of the cleats.

23. A machine for making boxes, comprising feed mechanism for successively engaging the cleats on the heads of the box, arranged to permit rotation of the box about a longitudinal axis, means for stapling sides to the said cleats, and means for controlling 70 said mechanism to permit successive rotation of the partially formed box at two corners thereof. 75

24. A machine for making boxes by fastening sides to heads, comprising mechanism for alternately feeding and turning the heads, means for inserting fasteners to 80 secure the sides on the edges of the heads, said mechanism including rolls for engaging the heads, and devices to intermittently rotate said rolls.

25. A machine for making boxes by fastening sides to heads, comprising mechanism for alternately feeding and turning the heads, and means for inserting fasteners to 85 secure the sides on the edges of the heads, said mechanism having guide rolls to engage the sides. 90

26. A machine for making boxes by fastening sides to heads, comprising mechanism for alternately feeding and turning the heads, and means for inserting fasteners to 95 secure the sides on the edges of the heads, said mechanism including rolls having a common horizontal axis and space between them for the heads.

27. A machine for making boxes by fastening sides to heads, comprising mechanism for alternately feeding and turning the heads, means for inserting fasteners to 100 secure the sides on the edges of the heads, said mechanism including rolls which support 105 the heads, means to operate said rolls, and means for engaging the sides to hold the heads in engagement with said rolls.

28. A machine for making boxes by fastening sides to heads, comprising mechanism 110 for alternately feeding and turning the heads, means for inserting fasteners to secure the sides on the edges of the heads, said mechanism including rolls for engaging the heads, and devices to intermittently rotate 115 said rolls, said mechanism having means to feed binding wire under the fasteners.

29. A machine for making boxes by fastening sides to heads, comprising mechanism for alternately feeding and turning the 120 heads, and means for inserting fasteners to secure the sides on the edges of the heads, said mechanism having guide rolls to engage the heads, said mechanism having means to feed binding wire under the fasteners. 125

30. A machine for making boxes by fastening sides to heads, comprising mechanism for alternately feeding and turning the heads, and means for inserting fasteners to 130 secure the sides on the edges of the heads,

- said mechanism including rolls having a common longitudinal axis and space between them for the heads, said mechanism having means to feed binding wire under the fasteners.
31. A machine for making boxes by fastening sides to heads, comprising mechanism for alternately feeding and turning the heads, means for inserting fasteners to secure the sides on the edges of the heads, said mechanism including rolls which support the heads, means to operate said rolls, and means for engaging the sides to hold the heads in engagement with said rolls, said mechanism having means to feed binding wire under the fasteners.
32. A machine for making boxes by stapling binding wire and sides and heads together, comprising mechanism for feeding the sides and heads, said mechanism having a roll to hold the sides down upon the heads, means to feed binding wire under said roll, and devices to staple the binding wire and sides to the heads.
33. A machine for attaching binding wire to sheets and cleats, comprising feed mechanism having upper rolls to bear down upon the sheets, means to feed binding wire under said rolls, and means to staple the binding wire to the sheets and cleats.
34. In a box making machine, a stapler, and means for moving the periphery of a box head across the stapler, said means supporting the portion of the box head in the region of the stapler only, the remainder of the box head being unsupported, said means permitting the discharge of the completed box from the machine in the general direction of the movement thereof across the stapler.
35. In a box machine for fastening sides to heads, in combination, a stapler and a box head feeding means having a material engaging portion which has feeding movement upwardly and a material engaging portion laterally distant therefrom which has feeding movement laterally in the same sense.
36. In a box machine for fastening sides to heads, in combination, a stapler and a box head feeding means having a material en-
- gaging portion which has intermittent feeding movement upwardly and a material engaging portion laterally distant therefrom which has synchronous feeding movement laterally in the same sense.
37. In a box machine for fastening sides to heads, in combination, a stapler and a head feeding device constructed and arranged for prehensile engagement with the peripheral parts of a box head, said device and the engaged head having a substantially hypocycloidal relative movement.
38. A box making machine, comprising, in combination, alining mechanisms each adapted for the direct application of a box head thereto, said mechanisms being constructed and arranged to give said heads alternate movements of translation and of rotation relatively to a line joining corresponding parts thereof, and staplers disposed substantially in a plane with said line for operation on said heads.
39. A box making machine, comprising, in combination, alining mechanisms each adapted for the direct application of a box head thereto, said mechanisms being constructed and arranged to give said heads alternate movements of translation and of rotation relatively to a line joining corresponding parts thereof, and staplers disposed substantially in a plane with said line for operation on said heads.
40. A box machine comprising alining synchronously moving mechanisms disposed with an unobstructed space therebetween, each of said mechanisms being adapted for the direct application of a box head thereto, said mechanisms being constructed and arranged to give said heads alternate movements of translation and of rotation relatively to a line joining corresponding parts thereof, and staplers disposed substantially in a plane with said line for operation on said heads.

Signed by me at St. Joseph, Michigan,
this 28th day of Feb. 1912.

JULIUS J. MILLER.
